UNITED STATES PATENT OFFICE.

ST. JOHN WOOD, OF NEW YORK, N. Y.

DESIGN FOR A CUT STONE.

SPECIFICATION forming part of Design No. 36,131, dated November 4, 1902.

Application filed August 15, 1902. Serial No. 119,828. Term of patent 14 years.

To all whom it may concern:

Be it known that I, ST. JOHN WOOD, of New York city, in the county and State of New York, have invented a new, original, and ornamental Design for a Cut Stone, of which the following is a specification, reference being had to the accompanying drawings, in which—

Figure 1 is a view in plan of the bottom of a cut stone embodying my design, and Fig. 2 a side elevation of the same.

The object of my invention is the production of a new, original, and ornamental design for a cut stone; and to this end my invention consists in the design for a cut stone, substantially as hereinafter specified.

My design, viewed in plan, comprises three concentric star-shaped figures, the innermost one being composed of a series of quadrilateral figures *a*, that radiate from the center and converge, meeting in an apex, the next being composed of a series of quadrilateral figures *b*, that each radiate from between two adjacent figures *a*, and the third being composed of a series of quadrilateral figures *c*, each radiating from one of the central figures

a and reaching the girdle of the stone. Lying between the points of each adjacent pair of figures *c* is a pair of triangular figures *d*. The figures *b* are not equilateral; but two sides of each one, such sides being those that adjoin the figures *a*, are much shorter than the other two sides, so that each figure has a long pointed form, and the appearance which is presented is that of a star with long slender points. It will be observed also by reference to Fig. 1 that each long side of one of the figures *b* coincides with one of the short sides of the adjacent figure *b*. The outline of a top is illustrated in Fig. 2 in a conventional way by dotted lines.

Having thus described my invention, what I claim is—

The ornamental design for a cut stone, substantially as herein shown and described.

In testimony that I claim the foregoing I have hereunto set my hand.

ST. JOHN WOOD.
